(57) **CLAIM**

The ornamental design for a fishing lure, as shown and described.

DESCRIPTION

FIG. 1 is a front perspective view of a fishing lure showing our new design;

FIG. 2 is a view taken from the right side;

FIG. 3 is a top plan view;

FIG. 4 is a bottom plan view;

FIG. 5 is a front elevational view; and,

FIG. 6 is a rear elevational view.

The broken line showing of environment in the drawings is for illustrative purposes only and forms no part of the claimed design.
